UNITED STATES PATENT OFFICE.

CHARLES L'ENFANT, OF NEW YORK, N. Y.

ASSEMBLING DEVICE FOR CARD CASES.

Application filed June 17, 1927. Serial No. 199,621.

This invention relates to an assembling device for card cases, and has for its primary object to provide a simple and inexpensive means whereby the outer flexible cover sheet of the case may be easily and quickly secured at its edges to the marginal edges of an inner flexible pocket-forming sheet or wall.

More particularly, the device is designed for use in the assemblage of the parts of the outer cover or holder for card cases of that type having a plurality of leaves or sections secured within the holder and provided with transparent windows forming additional card receiving pockets.

In one practical embodiment of the invention as herein shown, I provide a base of suitable dimensions upon which the parts of the card case cover are adapted to be arranged. Upon each edge of this base presser strips are hingedly attached, the adjacent ends of said presser strips being so formed and constructed that they may be folded inwardly without interference to lie in the same plane, and said strips thereby adapted to fold the marginal edges of the outer flexible sheet of the cover inwardly upon the marginal edges of the inner pocket-forming sheet. To the edges of this latter sheet, a suitable cement or adhesive gum is first applied to its opposite faces so that by the firm pressure of said hinged strips, the marginal edge portions of the inner and outer parts of the cover member become securely attached to each other. By means of such a device this assembling operation may be very quickly and accurately performed with the end and side inwardly folded edges of the material being neatly joined at the corners of the cover member.

It is another object of the invention to provide the base member adjacent its opposite ends with suitable upstanding guide pins adapted to be received through openings formed through the cover member adjacent its opposite ends, which openings are adapted to subsequently receive the male and female elements of a conventional snap fastening device.

With the above and other objects in view, the invention consists in the improved assembling device for card cases and in the form, construction and relative arrangement of its several parts as will be hereinafter more fully described, illustrated in the ac-

companying drawings, and subsequently incorporated in the subjoined claims.

In the drawing, wherein I have disclosed one simple and practical embodiment of the invention, and in which similar reference characters designate corresponding parts throughout the several views,—

Figure 1 is a plan view of the device, showing the parts of the card case cover arranged in position thereon; 65

Fig. 2 is a perspective view showing the hinged presser strips folded inwardly upon the base member;

Fig. 3 is a transverse sectional view of the device as indicated by the line 3—3 of Fig. 70 2, and

Fig. 4 is a plan view of the card case cover after the inner and outer parts thereof have been attached.

Referring in detail to the drawings, in 75 which I have illustrated one simple structural embodiment of the invention, 5 designates the base member which may consist of a slab of wood or metal, of the proper predetermined length and width. In this 80 base member in spaced relation to each end thereof and centrally between its side edges, an upstanding pin 6 is suitably secured.

To the opposite longitudinal edges of the base 5 the presser strips 7 are attached. As 85 herein shown, to the outer side face of each of these strips a plate 8 is secured by the screws 9, said plate projecting beyond the opposite ends of the strip 7 which is of somewhat less length than the length of the 90 base 5 and terminates in spaced relation to each end edge of said base. The metal plates 8 are hingedly connected as at 10 to similar plates 11 securely attached to the opposite longitudinal side faces of the base 95 5 by the screws 12. It will of course, be understood that if desired instead of providing the continuous plates 8 and 11 and a continuous connecting hinge 10, I may connect the strips 7 to the base 5 by means 100 of suitably spaced hinge plates, or provide any other desired form of hinge means which will permit of the strips 7 being moved from the positions shown in Fig. 1 of the drawings to the positions shown in 105 Fig. 2 thereof with respect to the base member 5.

Additional presser members 13 are similarly hingedly attached to the opposite ends of the base 5 as indicated at 14. 110

The side presser strips 7 at each of their ends are provided with the obliquely inclined surfaces 15 extending from the inner longitudinal faces of said strips to the relatively narrow end faces 16 which extend in planes parallel with the end faces of the base 5. The relatively movable presser members 13 are also provided with obliquely inclined surfaces 17 adapted to abut with the inclined surfaces 15 of the side strips, and at the outer end of each of the surfaces 17 with an angular shoulder 18 to abut against the narrow end faces 16 of the side strips.

In card cases of that type having a plurality of transparent card receiving pockets hingedly secured within an outer cover or holder, the cover member is composed of an outer face sheet 19 of leather or other composition material to the inner face of which the flexible lining sheet 20 is secured. A flexible pocket-forming wall or sheet 21 is arranged over this lining sheet. The outer face sheet 19 is of somewhat greater width than the lining sheet 20 and the pocket-forming sheet 21 so that the side and end marginal edge portions 22 of said outer face sheet project beyond the corresponding edges of the lining sheet. The flexible sheets 19 and 20, in spaced relation to their opposite ends are provided with the openings 23 therethrough, and these openings are adapted to receive the upstanding pins 6 on the base 5 of the assembling device, whereby the flexible sheets may be quickly arranged and held in proper position upon the upper surface of the base 5. The pocket-forming wall or sheet 21 which is of less length than the lining sheet 20 is then arranged in position as shown in Fig. 1 of the drawings. Thus, it will be apparent that the marginal edge portions 22 of the face sheet 19 extend outwardly over the hinges 10 and 14. Before the pocket wall or sheet 21 is arranged in place, the opposite longitudinal side edges thereof on one face of said sheet are provided with a suitable liquid cement or adhesive coating and the upper faces of the marginal parts 22 of the sheet 19 are coated with a similar adhesive.

After the parts have been arranged in position as above explained, the side strips 7 are first folded inwardly to the position shown in Fig. 2 of the drawings, thereby folding the marginal edges 22 of the face sheet 19 inwardly over and upon the corresponding edges of the lining sheet 20 and the pocket wall 21. The end members 13 are then similarly folded inwardly over the base so that the end marginal portions 22 of the face sheet of the cover are folded inwardly. It will be noted that the adjacent end edges of the side and end marginal portions 22 of the face sheet extend at right angles to each other so that when the end portions are folded inwardly, they will lap

upon the ends of the inwardly folded side portions 22. One end marginal portion 22 is secured only on the inner surfaces of the lining sheet 20 while the other end marginal portion 22 is secured also upon the extremities of the opposite side marginal portions of the pocket-forming sheet 21, it being noted that the opposite ends of this sheet 21 are cut out as at 24. The end presser members 13 are provided with suitably formed notches or recesses indicated at 25 to accommodate the upstanding pins 6 on the base when these members are folded inwardly to the positions shown in Fig. 2. By exerting a downward pressure upon the inwardly folded presser strips 7 and 13, the marginal edge portions 22 of the cover sheet are thus caused to firmly adhere to the lining sheet and the side edges of the pocket wall 21.

After the parts have been assembled as above described, the male and female elements of a snap fastener are secured in the openings 23, and the desired number of card receiving pocket inserts having windows of celluloid or other transparent material are arranged in position and extend substantially the full length of the pocket wall 21. They are then stitched centrally to said cover member across the width thereof. If desired, the inwardly turned marginal edges 22 of the face sheet of the cover may also be permanently secured by a line of stitching to the lining and the pocket-forming sheets. As will be seen from reference to Fig. 4, the pocket-forming sheet or wall 21 terminates at one of its ends in spaced relation to one end of the cover so that the projecting part of the cover sheet 19 and the lining sheet 20 constitutes a flap which is adapted to be folded over the other end of the cover member upon the outer side thereof and fastened by the fastening elements above referred to when the case is closed.

From the foregoing description considered in connection with the accompanying drawing, it will be seen that I have produced a very simple device which will greatly facilitate the quantity production of such card cases. By the aid of such a mechanical means, the several flexible parts or sheets constituting the cover member may be very accurately secured in assembled relation to each other and results in the desired uniformity of the product which it was not possible heretofore to secure by mere reliance on the skill of the workman. I have herein disclosed an embodiment of the device, which is simple in its construction and may be produced at nominal cost. It will however, be understood that this disclosure is largely suggestive and that my invention in its several essential elements might also be incorporated in various other alternative structures, and I accordingly reserve the privilege of resorting to all such legitimate

changes in the form, construction and relative arrangement of the several parts as may be fairly embodied within the spirit and scope of the invention as claimed.

5 I claim:

1. An assembling device of the character described comprising a base member upon the upper surface of which superimposed flexible elements are adapted to be arranged, 10 with the marginal edge portions of the lower flexible element projecting beyond the marginal edges of the other flexible element, and manually adjustable presser members hingedly connected to the marginal edges of 15 said base and adapted to be moved inwardly and downwardly into parallel relation with the upper surface of the base to thereby fold said projecting marginal edge portions of the lower flexible element inwardly upon the marginal edges of the other flexible element, said presser members initially having 20 their work engaging surfaces in the plane of the upper surface of the base member.
2. An assembling device of the character described comprising a base member upon the upper surface of which superimposed flexible elements are adapted to be arranged, with the marginal edge portions of the 25 lower flexible element projecting beyond the marginal edges of the other flexible element, presser strips hingedly connected to the opposite side edges of said base, additional presser members hingedly connected to the 30 end edges of said base, said presser members

initially having their work engaging surfaces in the plane of the upper surface of the base member and being adapted to be moved inwardly and positioned in parallel relation to the upper surface of the base to 40 thereby fold the projecting marginal edge portions of the lower flexible element upon the marginal edges of the other flexible element, and said presser members being received between the ends of said presser 45 strips and said strips and members having their end faces bevelled for abutting contact with each other.

3. An assembling device of the character described comprising an elongated rectangular base provided with means for positioning sheets of flexible material of relatively different widths in superimposed relation to each other upon the upper surface of said base, the wider sheet of material having 50 marginal edge portions projecting laterally from the other flexible sheets, side and end presser members hingedly connected with said base and movable from a position in laterally extending relation thereto to a 55 position above and in parallel relation to the base whereby said projecting marginal edge portions of the wider flexible sheet are folded inwardly and compressed upon the marginal edges of the other sheets. 60

In testimony that I claim the foregoing as my invention, I have signed my name hereto.

CHARLES L'ENFANT.
